(57) **CLAIM**

The ornamental design for a tremolo, as shown and described.

DESCRIPTION

FIG. 1 is a first perspective view of an ornamental design for a tremolo;

FIG. 2 is a second perspective view of the ornamental design for the tremolo;

FIG. 3 is a top view of the ornamental design for the tremolo;

FIG. 4 is a bottom view of the ornamental design for the tremolo;

FIG. 5 is a front view of the ornamental design for the tremolo;

FIG. 6 is a rear view of the ornamental design for the tremolo;

FIG. 7 is a left side view of the ornamental design for the tremolo;

FIG. 8 is a right side view of the ornamental design for the tremolo; and,

FIG. 9 is an enlarged perspective top view of the ornamental design for the tremolo.

The evenly spaced broken lines represent the portions of the tremolo and the remaining portions of a guitar environment that form no part of the claimed design. The dot-dashed broken lines in FIG. 9 indicate an enlarged portion of the design and form no part of the claimed design.
